UNITED STATES PATENT OFFICE.

HENRY K. PORTER, OF CHELSEA, MASSACHUSETTS.

BOLT-CLIPPER.

No. 830,453.

Specification of Letters Patent.

Patented Sept. 4, 1906.

Application filed August 31, 1905. Serial No. 276,513.

To all whom it may concern:

Be it known that I, HENRY K. PORTER, a citizen of the United States, residing at Chelsea, in the county of Suffolk and State of Massachusetts, have invented a new and useful Improvement in Bolt-Clippers, of which the following is a specification.

My invention relates to the class of such tools in which the cutting-blades are operated through compound levers, and is made adjustable by means of a novel construction illustrated in the accompanying drawings, in which—

Figure 1 is a plan of the tool embodying my invention, including a cross-section of the cutting blades or edges. Fig. 2 is an edge view of the same. Fig. 3 is an inner edge view of one of the handle-levers detached from the cutter-lever. Fig. 4 is a perspective of one of the pivotal handle-lever bolts and its cutting-lever bushing-block, which are employed to adjustably connect the handle-levers and cutter-levers. Fig. 5 is an elevation of the notched cutter-lever bolt and an under side plan of same. Fig. 6 is a cross-section on the devious line 6 6, Fig. 1. Figs. 7, 8, and 9 are different views of a modification which show a device independent of the handle-levers for preventing the movement with the cutter-levers of the adjusting-screws.

This clipper differs from others heretofore invented and patented by me mainly in the mode of adjusting the cutting edges through their actuating-levers. It comprises the usual pair of cutter-levers A A', having the cutting blades or edges B B' and interlocking teeth on the meeting edges of the cutter-levers, as shown in broken lines. The cutter-levers are pivoted by bolts C C', which pass through cross straps or plates D on opposite sides of the levers. The bolts C C' have left and right screw-threads, respectively, by which they are screwed into the lower cross-strap D, bolt C being left-handed and C' right-handed, corresponding to the movements of their respective cutter-levers when operated to cut, thus avoiding the tendency which might exist to turn the pivot-bolts by friction between the levers and bolts under the stress of cutting and to such an extent as to so clamp the levers between the straps as to render the use of the tool impracticable or impossible. To more positively guard the bolts against such frictional turning, I form notches or ratchet-teeth C²

in the under sides of the heads of the bolts, as shown in Fig. 5. The salient angles of these notches or teeth being properly tempered will resist such frictional turning of the bolts by biting into the softer surface of the strap against which they are turned, the ratchet-teeth under the heads being formed right-handed and left-handed, respectively, corresponding with the screw-threads on the bolts. The levers A and A' are also joined by bolts to the handle-levers E E' at A² A'³, while the handles are pivoted together at E². Thus far, with the exception of the ratchet-teeth under the heads of the bolts, this is old. The description will now depart from what is old.

The lever-handles are formed with branches G G', each of which describes an arc of a circle whose center is the pivot E². In the actuated ends H H' of the cutter-levers A A' are formed slots, one of which is shown in dotted lines at I', Fig. 1. These slots afford a limited movement of the ends of the cutter-levers independently of the action of the handle-levers with which they are joined. This is for purposes of adjustment, as follows: A block J, forming a partial bushing, is fitted in each of said slots, and through the block is passed the pivotal bolt K, as shown in the perspective, Fig. 4, and also through the handle-lever E', where it is secured by nut K'. These bolts and blocks are movable only with handle E E' around the pivot E². To accomplish the adjustment of the cutter-levers referred to above, a pair of adjusting-screws L L' are threaded laterally into the ends of the cutter-levers and extended through to the blocks. The arms or branches G G' on the handles embrace the ends of the pair of cutter-levers, somewhat like a spanner and serve as stops against the outer ends of the adjusting-screws to prevent their movement with the cutter-levers outwardly, and the blocks serve as stops against the inner ends of the screws to prevent such movement inwardly. To adjust the cutter-levers with reference to the cutting edges B B' in case of a wearing or breaking away of the edges so that it becomes necessary or desirable to adjust the edges closer together, the screws L L' are turned in a direction to screw them toward the blocks; but being confined between the blocks and handle branches no lineal advancement of the screws is practicable. Hence the action of the screws upon the cutter-levers is to draw the

levers toward the heads of the screws, and thus to close the cutting edges nearer together. A reversal of the adjusting-screws operates in like manner to separate the cutting edges. 5 The slots I afford sufficient play of the levers to effect such adjustment.

In lieu of the branches G, formed on the handles E, as shown and described, a device which I term a "bail," clearly shown in Fig. 8 10 and marked M, may be employed to support the adjusting-screws against endwise movement independently of the handles. The bail M is formed and adapted to embrace the combined cutter-levers and handle-levers 15 and to be secured thereto by the pivotal bolt K, the screw L in this case being formed with a pintle L², which passes through a hole in the bail, as shown, to keep the bail in right relation to the end of the screw to hold 20 the latter from endwise movement, thus serving the same purpose and as effectively as the branches G on the handles E.

I claim—

1. A bolt-clipper embodying the combination of a pair of pivoted cutter-levers having 25

slotted ends; a pair of handle-levers pivoted to each other, and joined to the cutter-levers by bolts through the slots in their ends; a pair of adjusting-screws threaded into the slotted ends of the cutter-levers; and means 30 arranged to hold the adjusting-screws in place against endwise movement thereof; all substantially as and for the purposes specified.

2. In a bolt-clipper, the combination of a pair of pivoted cutter-levers, having slotted ends; a pair of handle-levers, having curved arms formed thereon, and pivoted together and to the slotted ends of the cutter-levers; a pair of bushing-blocks fitted to the slots in 40 the cutter-levers, and held in place by the pivotal bolts; and a pair of adjusting-screws threaded into the slotted ends of the cutter-levers; all substantially as and for the purposes specified.

HENRY K. PORTER.
